United States Patent Office

Des. 177,703
Patented May 15, 1956

177,703

RECIPE HOLDER STAND

George White and Minnie White, Los Angeles, Calif.

Application August 30, 1955, Serial No. 37,717

Term of patent 14 years

(Cl. D44—29)

The figure on the drawing is a front perspective view of a recipe holder stand, showing our new design, the rear being plain and without any design motive.

We claim:

The ornamental design for a recipe holder stand, as shown and described.
